UNITED STATES PATENT OFFICE.

EMMETT M. HOWARD, OF BALTIMORE, MARYLAND, ASSIGNOR, BY MESNE ASSIGNMENTS, TO FRANK F. SLOCUM, OF PHILADELPHIA, PENNSYLVANIA.

PHONOGRAPHIC-DISK-RECORD EJECTOR.

1,425,771.

Specification of Letters Patent. Patented Aug. 15, 1922.

Application filed March 1, 1918, Serial No. 219,750. Renewed January 27, 1921. Serial No. 440,526.

To all whom it may concern:

Be it known that I, EMMETT M. HOWARD, a citizen of the United States, residing in the city and county of Baltimore, State of Maryland, have invented a new and useful Phonographic-Disk-Record Ejector, of which the following is a specification.

My invention consists of a novel construction of a phonographic disk record ejector wherein I have produced a structure embodying a series of closely related vertical parallel compartments capable of accommodating or storing and ejecting records of varying diameters, which I effect by the employment of vertical partitions, preferably formed of thick paper or thin pasteboard, or the like, having their front edges stripped, which partitions are firmly seated at their upper and lower edges in cuts, slots or kerfs in the top and bottom of the enclosing box or casing thereby forming the ejector skeleton, the lower portions of said partitions having passed therethrough the fulcrum rod which supports the ejector levers, said partitions thereby serving as a plurality of supports therefor.

It further consists in collocating the fulcrum rod, the record holding compartments and the ejector levers in a novel manner, whereby, when a compartment is empty the record supporting and ejecting lever will be inclined downwardly and outwardly so as to serve as an indicator or telltale to indicate the proper compartment into which to re-

place the record.

It further consists, in conjunction with said levers and partitions, of a novel collocation therewith of an abutment or bumper which is located in the rear of the fulcrum rod at the point where the arcs or rear peripheries of different sized records coincide in a horizontal line, whereby records of varying diameters are arrested at the proper period of their rearward travel and are so positioned as to be readily engaged by the depression of the desired lever when a predetermined record is desired.

To the above ends, my invention consists of a novel construction of a phonographic disk record cabinet having vertical partitions whose extremities are seated in the top and bottom of the enclosing box or casing, the lower portion of said partitions serving as supports for the fulcrum rod passing transversely therethrough in which is pivoted

the oscillatory record receiving and ejecting levers, the latter having a bumper located in the rear thereof in a novel position, said fulcrum rod being supported in said partitions at such a point that when a record compartment is empty, the front end of the ejector lever will incline downwardly, thus serving as a tell-tale or indicator to indicate at a glance the proper compartment wherein to replace the record.

For the purpose of illustrating my invention, I have shown in the accompanying drawings embodiments which are at present preferred by me, since the same in practice will be found to give satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a perspective view of a phonographic disk record cabinet embodying my invention.

Figure 2 represents a section on line 2—2 of Figure 1.

Figure 3 represents a section on line 3—3 of Figure 2.

Figure 4 represents a perspective view of one of the record supporting and ejecting levers in detached position.

Similar numerals of reference indicate corresponding parts in the figures.

Referring to the drawings:

1 designates the enclosing box or casing having a top 2, bottom 3, sides 4 and rear wall 5, which latter may, however, be omitted, if desired.

The under surface of the top 2 and the upper surface of the bottom 3 are provided with longitudinally extending cuts or kerfs 6 and 7 which I preferably make in one operation by a plurality of saws, said cuts being in exact vertical alignment and serving as seats for the top and bottom edges of the partitions 8, whose front edges are bound or stripped with a suitable fabric or reinforce 9. The partitions 8 may be of thin pasteboard, cardboard, paper or similar non-abrasive material and after having their opposite ends treated with adhesive material, they are slid into position as indicated in Figure 3, thereby forming a skeleton having the vertical, parallel closely related record

holding compartments 10 of one maximum vertical dimension which are adapted for the reception of records 11 of varying diameters. At the lower portion of each record holding compartment, I locate the oscillatory record supporting and ejecting levers 12, the same forming the bottoms of the compartments. Said levers have their outer ends bevelled, as indicated at 14, and on the top of the outer portions thereof I place numerals in consecutive order, each numeral corresponding to a number on the record supported and to a number on an index card (not shown). The ejector levers are preferably all alike and can be cheaply constructed out of wood, having plain upper and lower faces, said levers being assembled on their fulcrum rod 15, whose ends are anchored in the sides 4, the intermediate portions of said rod being supported in the lower portions of said partitions 8 through which said rod passes. If desired, the upper rectilinear face of the ejector levers, which forms a track for the records, may be slightly grooved or concave, as at 13, but this is not necessary in practice. It will further be understood that in practice the rear lower end of the ejector lever when the records are in their rearmost position, contacts with the top surface of the bottom of the casing, and that when the record has been ejected, or in other words, when the record compartment is empty, the outer bottom surface of the ejector lever contacts with the upper surface of the bottom of the casing at the front thereof, the outer bevelled terminals being so located that when the compartments are full, said bevelled surfaces will horizontally align at the bottom of the casing.

The partitions 8 serve a dual function since they not only provide efficient record containing compartments having non-abrasive sides which enable records of varying diameters to be stowed away and ejected without injury to the sound producing grooves thereon, but these walls also furnish a plurality of supporting points for the fulcrum rod 15, as is evident.

16 designates an abutment or bumper which is positioned substantially as shown in Figure 2 at that point where the rear arcs or peripheries of the various sized records coincide in a transverse horizontal line when at rest, so that a single bumper suffices for all records of varying diameters. In order that the records may not hop, jump or bounce when ejected, I attach a finger or abutment 17 to the rear end of each ejector lever, which is positioned at such a point that upon the depression of the outer end and the consequent elevation of the inner end of any ejector lever, said finger 17 will immediately contact with the juxtaposed arc of the record to be ejected and the latter

will roll gently forwardly to be caught in the hand of the operator. When the records are at rest in their rearward position, the upper end of the finger 17 is preferably about $\frac{1}{16}$ or $\frac{1}{32}$ of an inch from the arc 70 of the juxtaposed record.

I position the fulcrum rod 15 in its supporting partitions so that the center of gravity of a lever will be at a point between the fulcrum and the outer end of the lever, so 75 that when a record is ejected, the outer front or forward end of the tilting supporting lever will drop and will always normally be in a depressed position when a compartment is empty (see the lever numbered 6, Figure 80 1), thereby serving as an indicator or tell-tale to indicate at a glance the proper compartment in which to insert the record after use. It will be evident that if desired the same result may be attained by weighting 85 the outer or front end of each ejector lever.

To replace a record within the cabinet, it is only necessary to place it in its proper compartment resting on its proper lever, which as above explained will be depressed, 90 at its forward end when the compartment above it is empty, and to give it a slight push rearwardly, whereupon the record will roll rearwardly by gravity and upon passing the fulcrum will descend to rest against the 95 bumper 16, the inner end of the lever 12 then resting upon the bottom wall 3. It will be apparent that by collocating the ejector levers 12 in the manner shown and giving to their outer ends the uniform bevel 14 100 upon which the numerals are placed that when all the compartments are filled said bevelled ends are in horizontal alignment thus giving a pleasing appearance to the front of the cabinet and in addition enabling 105 the tell-tale lever indicative of the empty compartment to be more readily visible, as will be understood from Figure 1.

It will now be apparent that I have devised a novel and useful construction of a 110 phonographic disk record ejector which embodies the features of advantage enumerated as desirable in the statement of the invention and the above description, and while I have, in the present instance, shown and described preferred embodiments thereof which will give in practice satisfactory and reliable results, it is to be understood that the same are susceptible of modification in various particulars without departing from the 120 spirit or scope of the invention or sacrificing any of its advantages.

Having thus described my invention, what I claim as new and desire to secure by Letters Patent, is:—

1. In a phonographic disk record cabinet, a box having its top and bottom provided on their inner surfaces with parallel aligning cuts, partitions of non-abrasive material having their upper and lower ends seated in 130

said cuts, thereby forming closely related parallel, non-abrasive record holding compartments adapted for the reception of different sized records, a stripping of non-abrasive material for the front vertical edges of each of said partitions, a series of oscillatory record supporting ejector levers consisting of straight bars having upper rectilinear faces located at and forming the bottoms of said compartments, a fulcrum rod passing transversely through said levers at the rear of their center of gravity, whereby the forward end of a lever when a compartment is empty gravitates downwardly and outwardly to form a tell-tale to indicate an empty compartment, the front underside of each lever then contacting with the bottom of said box, while the rear terminals of said levers when a record is in its rearmost position also contact with the bottom of said box, a bumper located above said levers in the rear portion of said box, and a finger at the rear portion of each of said levers for coaction with the juxtaposed periphery of a record when it is desired to eject the latter.

2. In a phonographic disk record cabinet, a box having its top and bottom provided on their inner surfaces with parallel aligning cuts, partitions of non-abrasive material having their upper and lower ends seated in said cuts, thereby forming closely related parallel, non-abrasive, record holding compartments adapted for the reception of different sized records, a series of oscillatory record supporting ejector levers consisting of straight bars having upper rectilinear faces located at and forming the bottoms of said compartments, a fulcrum rod passing transversely through said levers at the rear of their center of gravity, whereby the forward ends of said levers when a compartment is empty incline downwardly and outwardly to form a tell-tale to indicate an empty compartment, the front underside of each lever then contacting with the bottom of said box, while the rear terminals of said levers when a record is in its rearmost position also contact with the bottom of said box, and a bumper located above said levers in the lower rear portion of said box at the point where the lower inner peripheries of different sized records coincide in a rectilinear line when at rest, said levers having a finger at their rear portions for coaction with the juxtaposed periphery of a record.

3. In a phonographic disk record cabinet, a box having a top and bottom and provided with a series of vertical partitions of non-abrasive material having their upper and lower ends secured to said top and bottom to form closely related parallel, nonabrasive record holding compartments all of one maximum vertical dimension and adapted for the reception of records of varying diameters, a stripping of nonabrasive mate-

rial for the front vertical edges of said partitions, a series of oscillatory record supporting ejector levers, located at and forming the bottoms of said compartments, a fulcrum rod passing transversely through said levers and supported in said partitions, whereby the front underside of a lever when depressed may contact with the bottom of said box, while the rear bottom end of such lever when a record is in rearmost position thereon also contacts with the bottom of said box, the forward terminals of said levers having a uniform contour and all said terminals being in horizontal alignment when said compartments are filled or empty, and the rear ends of said levers having an abutment projecting upwardly at an angle thereto for coaction with the juxtaposed periphery of a record, and a bumper located above said levers in the rear of said box.

4. A phonographic disk record cabinet, having a top and bottom and provided with a series of vertical partitions of nonabrasive material having their upper and lower ends secured to said top and bottom to form closely related, parallel, nonabrasive record holding compartments, all of one maximum vertical dimension and adapted for the reception and ejection of records of varying diameters, a series of oscillatory, record supporting ejector levers, consisting of straight bars having rectilinear top and bottom faces located at and forming the bottom of said compartments, a fulcrum rod passing transversely through said levers at the rear of their center of gravity, whereby the forward end of a lever, when a compartment is empty gravitates downwardly and outwardly to form a tell-tale to indicate an empty compartment, the front underside of such lever then contacting with said bottom, while the rear bottom end of such lever, when a record is in rearmost position thereon also contacts with said bottom, the forward terminals of said levers being in horizontal alignment when said compartments are filled and the forward ends of said levers raised, and an abutment at the rear end of each of said levers projecting upwardly at an angle thereto for coaction with the juxtaposed periphery of a record.

5. In a device of the character stated, an ejector skeleton for housing and ejecting disk records comprising a series of vertical, closely related, parallel disk record holding compartments, pivoted ejector levers forming the bottoms of said compartments and having a rectilinear top upon which the records are supported and rolled during insertion and ejection, a horizontal, transversely extending bumper located at the lower rear portion of said skeleton at the point where the lower rear peripheries of different sized records align in a horizontal line when in their rearmost stowed position, and an abut-

ment on the upper rear portion of each of said levers, and positioned when a lever is loaded at a point below, forward of, and in proximity to, said bumper for effecting the noiseless ejection of a record.

6. As an improved article of manufacture, a cabinet for the reception and ejection of phonographic disk records, having a horizontal series of vertical, parallel, closely related record holding compartments having partitioning devices therebetween, all of one maximum vertical dimension and all capable of receiving and ejecting records of different diameters, a transversely extending bumper located in the lower rear portion of said cabinet at the point where the arcs of different sized records coincide when at rest in stowed position, and record supporting and ejecting means for each compartment comprising rectilinear ejector levers located at and forming the bottom of each of said compartments and having their fulcrum located at the rear of their center of gravity, whereby when a compartment is empty, the

forward end of its lever gravitates downwardly, thereby acting as a tell-tale to indicate an empty compartment.

7. A disc record cabinet, comprising a casing, vertical partitions therein forming parallel, closely related, record holding compartments, ejector levers fulcrumed in and forming the bottoms of said compartments and having a top surface upon which the record is supported and travels and an upwardly projecting short abutment at the rear end of each lever for impacting against the juxtaposed periphery of the record to effect the noiseless ejection thereof, and a fulcrum rod extending transversely through said levers at a point in the rear of their centers of gravity, whereby the front end of an unloaded lever will gravitate downwardly to serve as a telltale to indicate an empty compartment.
